Application September 9, 1954, Serial No. 32,224

Term of patent 14 years

(Cl. D91—3)

Fig. 3

To all whom it may concern:

Be it known that I, James A. Tiller, a citizen of the United States, residing at Louisville, State of Kentucky, have invented a new, original, and ornamental Design for a Spout, of which the following is a specification, reference being had to the accompanying drawing, forming a part hereof.

Fig. 1 is a perspective view of a spout showing my new design,

Fig. 2 is a view in side elevation thereof, and
Fig. 3 is a view in front elevation thereof.

The dominant features of my design reside in the portions shown in full lines.

I claim:

The ornamental design for a spout, substantially as shown and described.
